(57) CLAIM

The ornamental design for a chair, as shown and described.

DESCRIPTION

This application is related to design patent application Ser. Nos. 29/305,602; 29/305,603; 29/305,605; 29/305,606; 29/305,607; 29/305,612; and 29/305,615, which are filed concurrently herewith.

FIG. 1 is a perspective view showing the front, left side, and top of a chair showing my new design; and,

FIG. 2 is a left side elevational view, the right side elevational view being a mirror image thereof.

The broken lines shown in FIG. 1 are for illustrative purposes only and form no part of the claimed design.

1 Claim, 2 Drawing Sheets
